[57] ABSTRACT

A line card circuit for a key telephone system in which means are provided for sensing ringing current on the line conductors the card is connected to. Also included are means to connect audible and visual signal equipment and to effect placement of the connected line in a hold condition.

LINE CARD CIRCUIT FOR A KEY TELEPHONE SYSTEM

BACKGROUND OF THE INVENTION

1. Field of the Invention

This invention relates to telephone systems and more particularly to subscriber operated telephone equipment generally known as key telephone switching systems.

2. Description of Prior Art

Key telephone systems are systems controlled by the subscriber which permit the use of one or more subscriber station sets with a plurality of telephone lines by permitting selective switching of one line or another to the subscriber station. Key telephone switching systems provide a variety of control and supervisory functions necessary for the utilization of several telephone lines by each multi-line subscriber station.

In the present day subscriber's key telephone system each telephone line controlled by a multi-line subscriber station set has associated therewith a line card. Each line card contains the necessary circuitry to perform the desired switching and supervisory functions required by the associated line regardless of how many station sets have access to the line. These functions include audible and/or visual signals to the subscriber in addition to the detection of ringing current received from a central office or a private branch exchange switching system. Also provided is the ability to place a "hold" condition on the line so that the subscriber may use his subset for another line without losing the call, the detection of the abandonment of an incoming call and a consequent returning of the line card to an idle condition, the answering of an incoming call by allowing a subset connection to the incoming call line and call origination from the subscriber station by seizure of a selected line.

Because of the variety of functions to be performed each line card circuit is usually limited in its operation to a single line. With the considerably expanded utilization of key telephone units and associated multiple line facilities, it is highly desirable to reduce the complexity, size and cost of such line cards while increasing the reliability of the circuitry contained thereon. Present line cards, while satisfactory for utilization in most key switching systems, suffer from a variety of problems.

Originally line cards utilized large numbers of relays to sense the presence of ringing signals associated with an incoming call and perform the various required switching and holding operations. Such multiple relay sensing and switching circuits because of the quantity of relays involved are large in size and the operate and release times of the relays limit the speed of the switching operations. To overcome the deficiencies of multiple relay line circuits, transistorized sensing and switching circuits or hybrids employing both transistors and relays have become more or less standard. Such units are disclosed in U.S. Pats. No. 3,239,610 to C. E. Morse, et al., No. 3,436,488 to R. E. Barbato et al., Nos. 3,647,983 and 3,649,772, both to A. R. Fitzsimons et al. While such units do reduce the physical size of line card units, they too, produce a variety of problems. Such problems include increase of the total number of components and a tendency towards false ringing. Certain of the designs shown in the above patents also include a certain percentage of transmission loss

through the line card, a susceptibility to damage caused by lightning and on incoming calls the timeout interval is dependent on the number of previous rings. Other problems inherent in prior art line cards include a tendency to give false incoming call indications because of power line transients and poor voice transmission properties because of insertion loss and longitudinal unbalance. Many of the problems of line card design are overcome in my copending application Ser. No. 10 318,143 filed Dec. 26, 1972, the present invention being an improvement thereon.

SUMMARY OF THE INVENTION

The present invention comprises a novel line card circuit for use with a multi-line subscriber's key telephone, located at the subscriber's premises to perform all the necessary sensing and switching functions. Sensing means are provided to detect the presence of ringing signals on the line conductors coming from a telephone central office or private branch exchange. The sensing means comprises a double winding relay with both windings connected in series during the ringing operation. While readily responding to ringing signals, the sensing relay is not sensitive to telephone line or supply voltage transients.

Means are further included operative in response to the operation of the sensing relay, but electrically isolated from line ringing signals to provide signals to lamps and/or buzzers associated with each key telephone connected to the present line card. A holding resistance is also included in the line card, that is readily connectable across the line conductors in response to the subscriber placing the line in the hold condition in order to answer another call. This placement of the holding resistance across the line conductors in a bridging configuration prevents the loss of the connected call.

Means are included when the subscriber answers an incoming call to effectively shunt the sensing relay eliminating insertion loss and longitudinal unbalance and at the same time extinguishing the audible signal and changing the visual signal from a characteristic flashing lamp signal to a steady lamp signal indicating the presence of a completed circuit connection between the subscriber's telephone set and the central office or private branch exchange. Operation of a hold key associated with the subscriber station not only causes placement of the holding bridge referred to above but also causes the visual signal to change from a steady lamp to a winking lamp signal which is operated at a characteristic rate different from the flashing lamp signal associated with an incoming call. The subscriber reconnects his telephone to a held line in the same manner as answering an incoming call.

In the present invention the line card circuit is of the hybrid type utilizing both relays, transistors and associated circuit components. The circuit design is such that such features as good voice transmission properties, more stable time out interval lengths, faster switching times and prevention of false operation are all included while circuit components are essentially no greater in number than that of prior art designs.

BRIEF DESCRIPTION OF THE DRAWING

The single FIGURE of drawings appended hereto is a schematic circuit diagram of a line card circuit constructed in accordance with the principles of the pres-

ent invention, shown connected to a single key telephone and to a power supply and interrupter circuit of conventional construction and well known in the prior art, which provide the necessary power and supervisory signals for use with the present invention. While but a single key telephone is shown connected to the line card, it is to be understood that a plurality of telephones may be connected thereto and that only those portions of the key telephone that are required for operation of the present invention are shown. The remaining portions not shown for the sake of convenience and clarity in description of the present invention are all well-known in the art.

It should also be noted that the relay and key circuitry included in the present drawing are in accordance with the technique referred to as detached contact circuitry. In the detached contact form of circuitry the contacts associated with a particular relay coil are distributed throughout the circuit drawing but are identifiable by a letter prefix designation similar to that of the relay coil. An X crossing a circuit lead indicates a make contact while a short single line perpendicular to a circuit lead indicates a break contact in this format.

DESCRIPTION OF THE PREFERRED EMBODIMENT

Referring now to the single FIGURE of drawings a subscriber's key telephone is shown connected via the line card of the present invention to a telephone central office or private branch exchange. As noted above, only those portions of the subscriber's key telephone whose operation is associated with the present line card circuitry are shown. These include a telephone transmission network 103 connected across the T and R leads extending to the central office and include in the R lead, pick-up key contacts K1A and switch hook contacts S1A while included in the T lead connection are pick-up key contacts K1B. Also included and connected to the supervisory or A lead are pick-up key contacts K1C, switch hook contacts S1B and a hold key K2. Further shown is a visual indicating lamp LP1 and a buzzer 104. It should be understood that the buzzer 104, as an audible signal device, is an arbitrary selection and a conventional telephone ringer could be substituted at this point. Also connected to the line card circuitry is power supply 101, which is likewise connected to interrupter 102. Power supply 101 provides the necessary operating potentials for use with the line card, interrupter 102 and the associated key telephone. Interrupter 102 provides the specific signaling potentials connected through the line card to the audible and visual signaling devices included in the subscriber's key telephone.

The line card circuitry itself shown in schematic form includes line sensing relay L, which is a two winding relay, which operates during ringing and during the hold operation, relay B which also operates during ringing and during the hold operation, relay A which operates during the "off-hook" or operated condition, and relay C which operates during the "off-hook" condition and is also operated during the holding condition. Associated with the operation of relay B are transistors Q1, Q2 and Q3 and their associated biasing circuitry.

For the best understanding of the present invention, operation of the circuitry during the various functions associated with the key telephone will be described.

Initially, when the circuit is idle, all relays are in their restored or normal condition while all transistors are in their OFF condition and capacitor C1 is discharged. It should be assumed that any subscriber's key telephone sets connected to the line card are in the "on-hook" condition, the supervisory lamp LP1 is unlit and the A lead is disconnected from ground because pick-up key contact K1C is not operated.

When an incoming call is received from the telephone central office or private branch exchange, ringing current will be applied to conductors T and R and current will flow through both coils of relay L over a path that may be traced from terminal R extending to the central office or private branch exchange through the upper coil of relay L (A) through break contact C2, resistor R4 and the second or lower coil L (B) and then through capacitor C2 to the conductor extending to terminal T connected to the telephone line extending to the central office or private branch exchange.

In response to this ringing voltage contacts L1 of relay L will close and open during each half cycle of ringing, causing capacitor C1 to charge over a path extending from ground through contacts L1, resistor R3 and capacitor C1 to battery. When the voltage of capacitor C1 reaches about half the normal power supply voltage, transistor Q1 will be turned ON by its base lead through resistor R5. Operation of transistor Q1 is effective to turn ON transistor Q2 which in turn turns transistor Q3 ON. When transistor Q3 turns ON, relay B operates. Operation of relay B at contacts B5 turns on interrupter 102 and at make contacts B4 extends ringing potential to buzzer 104 included in the subscriber's key telephone subset. At contacts B3 flashing lamp potential is extended to lamp LP1 causing it to flash at a rate indicative of an incoming call. Capacitor C1 continues to charge during ringing, maintaining the charge level high enough to keep transistor Q1 in conduction, and therefore causing transistors Q2 and Q3 to remain ON and relay B to remain operated. At this point the presence of an incoming call is indicated at each key telephone connected to the present line card by virtue of the flashing lamp and buzzer signals.

If the incoming call is abandoned before the subscriber answers the call, such as happens when the calling party of the central office or private branch exchange goes back "on-hook," capacitor C1 will start to discharge after the last ring. When the charge level drops to about half the supply voltage transistor Q1 will turn OFF, in turn turning transistors Q2 and Q3 also OFF and restoring relay B to normal and hence restoring the line card to its idle condition.

To answer the incoming call, the subscriber will at one of the key telephones connected to the present line card go off-hook operating switch hook contacts S1A and S1B as well as operating pick-up key K1 completing connections between the conductors extending to the telephone central office at contacts K1A and K1B and completing the supervisory path at contacts K1C. Operation of the switch hook contacts and the pick-up key will place the transmission network 103 across the station leads R and T, which will cause ringing signals to cease at the central office or private branch exchange and relay L to restore. The connection of ground to the A lead causes relay A to operate. At make contacts A2 the current path for transistor Q1 is broken discharging capacitor C1 and turning transistor Q1 OFF. This causes transistors Q2 and Q3 to turn

OFF and restores relay B. The restoration of relay B at break contacts B2 completes a path to ground through contacts A3 to operate relay C. Operation of relays B and C will at contacts B3, B4, B5, C5, C6 and A4 stop the flashing lamp signal as well as stop the audible signals from buzzer 104 and extend a steady potential to supervisory lamp LP1. At make contacts A1 and C1 a talking path will be completed from the R terminal extending to the central office around the upper winding of relay L (A) to the key telephone. At this point conversation between a subscriber at a key telephone subset connected to the present line card and the subscriber initiating the incoming call may commence.

If the subscriber desires to place the line on hold, he will operate hold key K2 moving ground from terminal A. This will cause the restoration of relay A, removing the shunt at contacts A1 from the upper winding of relay L (A). Relay L at its upper winding L (A) will now operate from loop current from the telephone central office or private branch exchange extending through the transmission network 103. With the operation of relay L at contacts L1, operating current through contacts C3 and diode CR1 will be provided to operate relay B, and charging of capacitor C1 will start through resistors R12 and contact C2. At contacts B2 a holding path through resistor R14 is established to hold relay C operated. When relay B operates, resistor R1 is connected across the line through make contacts C2 and B1 and the upper coil of relay L (A), to maintain loop current. This is the holding bridge required to hold a circuit connection to the telephone central office or private branch exchange. Operation of contacts C5 and A4 provide the lamp wink signal to lamp LP1, providing an indication of the hold condition. The telephone line associated with the line card is now in the hold condition.

Should the subscriber wish to re-answer a line in the hold condition, the hand set associated with the key telephone must be removed from the switch hook to operate switch hook contacts S1A and S1B and the pickup key K1 must also be operated to reconnect the subscriber's telephone to the line in the hold condition. The operation of switch hook contacts S1A and pickup key contacts K1A and K1B will reconnect the key telephone network 103 to the telephone line. Operation of the switch hook S1B contacts and pick-up key K1 contacts will reconnect ground to terminal A. This ground will re-operate relay A. Relay A, at contacts A4 will connect steady 10 volt potential to lamp LP-1, and shunt relay coil L (A) at contact A1. When relay L restores, relay B is held operated momentarily by the charge on capacitor C1 through resistor R12 and diode CR1, assuring that the holding resistor R1 will remain across the line until after the key telephone's network 103 is replaced across the line. Also, the delay in restoration of relay B insures that a false "dial-1" transfer pulse is not generated. Restoration of relay B then removes at contact B1 the holding resistors R1.

If where a line is in the held condition, and a central office or private branch exchange subscriber desires to terminate the call, the circuitry of the present line card is able to release the held line when the central office or private branch exchange momentarily opens the loop. When this takes place relay L which has been held operated by virtue of loop potential through its upper winding L (A), will restore. After a delay (resulting from the partial discharge of capacitor C1), relay

B restores, disconnecting the holding resistor R1 from the line, and disconnecting ground through resistors R14 and make contact B2, from relay C, causing relay C to restore. At this point all the relays included in the present line card circuit will have been restored and all transistors are in their OFF condition. The restoration of both relays B and C will at contacts C5 remove the lamp wink signal from LP1 and lamp LP1 will revert to its extinguished or off-state. This serves as an indicator to the subscriber that the central office or PBX connection no longer exists.

When a subscriber at the associated key telephone connected to the present line card wishes to release a connected line, restoration of pick-up key K1 will at contacts K1A and K1B disconnect the network 103 from the line, eliminating loop current. Likewise at contacts K1C ground will be removed from terminal A. Alternately, restoration of switch hook contacts S1A and S1B will also release the line. In this manner relay A will restore followed by restoring of relay C, returning the line card to the idle condition in a manner similar to that outlined above.

When the line card is in the idle condition, if a subscriber at the associated key telephone subscriber's unit desires to initiate a call, he will operate the pick-up key and at contacts K1A, K1B and K1C complete the circuit connections outlined above as well as remove the handset from the hook switch to further complete the circuitry at switch hook contacts S1A and S1B. The placement of ground on terminal A will cause operation of relay A which in turn will at make contacts A3 provide operating ground to relay C. This provides a shunt around the upper winding relay L (A) at contacts A1 and C1. A steady lamp signal will be sent to the lamp at the subscriber's unit by virtue of operation of make contacts C5. At this point the dial tone should normally be returned from the telephone central office or private branch exchange to be heard by the subscriber in his handset (not shown) after which he may initiate a call by operating a calling device (not shown) associated with the subscriber's key telephone unit.

While but a single embodiment has been shown in the present invention it should be obvious to those skilled in the art that numerous modifications and variations on the present design may be made without departing from the spirit and scope of the present invention which is limited solely by the claims appended hereto.

What is claimed is:

1. A telephone line circuit for use with telephone systems including at least one key telephone subscriber's set and a pair of line conductors to which ringing signals and line current are applied and which are adapted to be connected through said key telephone set by operation thereof, said telephone line circuit comprising: first means comprising a multi-winding first relay normally connected with said windings in series between said line conductors, said first relay initially operated in response to alternating current ringing signals applied to said line conductors and conducted over said conductors to said serially connected relay windings; second means including a second relay connected to said first relay, operated in response to said operated first relay, to enable audible and visual indicators at said key telephone subscriber's set; and third means including a third relay operated in response to operation of said key telephone subscriber set to render said second

means inoperative to disable said audible and visual indicators; said first means further rendered inoperative in response to operation of said key telephone subscriber set.

2. A telephone line circuit as claimed in claim 1 wherein: said second means further include at least a first transistor connected between said first relay and said second relay, said first transistor rendered conductive in response to operation of said first means and said second relay operated in response to said first transistor being rendered conductive.

3. A telephone line circuit as claimed in claim 1 wherein: said third means further include a fourth relay operated in response to operation of said third relay, to reenable said visual indicator in a second manner distinct from said original enablement.

4. A telephone line circuit as claimed in claim 1 wherein: said third relay in response to further operation of said key telephone subscriber set is rendered in-

operative thereby connecting one of said windings of said first relay between said line conductor and said subscriber set rendering said first relay re-operable; said first relay re-operated in response to line current applied to said line conductor; said second relay re-operated in response to said re-operation of said first relay; said fourth relay held operated in response to said re-operation of said second relay; said re-operation of said second relay and continued operation of said fourth relay in combination effective to connect a bridge circuit between said line conductors, shunting said key telephone subscriber set; said reenablement of said second relay and holding of said fourth relay operated in combination further effective to disable said visual indicator operated in said second manner and reenable said visual indicator in a third manner distinct from said second manner and from said original enablement.
